UNITED STATES PATENT OFFICE.

JOSEF ELLMAUER, OF MILWAUKEE, WISCONSIN, ASSIGNOR TO REFRIGO CORPORATION, OF MILWAUKEE, WISCONSIN, A CORPORATION OF WISCONSIN.

AUTOMATIC PRESSURE SAFETY CONTROL.

Application filed May 5, 1921, Serial No. 467,064. Renewed February 11, 1924.

To all whom it may concern:

Be it known that I, JOSEF ELLMAUER, a citizen of the United States of America, residing at Milwaukee, in the county of Milwaukee and State of Wisconsin, have invented certain new and useful Improvements in Automatic Pressure Safety Controls, of which the following is a specification.

The primary object of the invention is the automatic control of the fluid pressure system of refrigerating apparatus and more especially relates to a fluid pressure diaphragm for actuating the electrical switch controlling motor of the compressor for the system.

A further object of the invention is the provision of a diaphragm actuated switch with automatic means for cutting off the supply of fluid in the event of accidental breaking of the diaphragm.

A still further object of the invention is the provision of a diaphragm actuated controlling switch for a fluid pressure plant, and having a quickly operating or snap-motion whereby the opening and closing of the electrical circuit takes place quickly, preventing arcing of the current.

With these general objects in view, the invention consists of the novel combination and arrangement of parts hereinafter more fully described in connection with the accompanying drawing and in which like reference characters designate corresponding parts throughout the several views.

In the drawing,

Figure 1 is an end elevation of the device installed for operation,

Figure 2 is a vertical longitudinal sectional view of the device with the electric switch mechanism shown in side elevation, and

Figure 3 is a detail elevational view of the valve seat within the diaphragm casing.

Referring more in detail to the drawing it will be first understood that it is desirable to maintain the fluid pressure in the piping or system of a refrigerating apparatus substantially constant which can be effected by the starting and stopping of the electric motor furnishing power for the compressor acting upon the refrigerating fluid of the system. The pipe 10 herein illustrated communicates with the piping system so as to receive the fluid under pressure and conduct the same into the central chamber 11 of a diaphragm casing formed in two

sections 12 and 13 secured together by bolts 14. A diaphragm 15 of suitable flexibility is secured between the sections 12 and 13 dividing the chamber 11 into substantially two equal parts, a gasket 16 of lead or similar metal being secured between the marginal portion of the diaphragm 15 and the casing section 12.

The pipe 10 being tapped centrally through the casing section 12 into what is herein termed the forward portion of the chamber 11 has a lead gasket 17 overlying its inner end and spun over into an annular groove 18 formed by a central boss 19 upon the inner face of the section 12 and acting as a valve seat around said fluid pressure pipe 10. A valve 20 within the outer portion of the chamber 11 has a rounded face normally engaging the adjacent side of the diaphragm 15 with a stem 21 slidably positioned through a central perforation 22 in the casing section 13.

Adjustable actuating means for the valve 20 consists of inner and outer heads 22 and 23 respectively herein illustrated in the form of circular disks rigidly connected together by bolts 24 sliding through openings 25 and 26 in the casing sections 12 and 13 with said heads positioned upon opposite sides of the casing. The outer end of the valve stem 21 is maintained in constant engagement with the center of the outer head 23 by means of springs 27 surrounding the bolts 24 and tensioned between the head 22 and the casing section 12, it being noted that the head 22 is freely mounted upon the pipe 10 by means of a central opening 28 in the head 22 through which the pipe 10 extends, acting as a guide. Variations in pressure of the fluid within the pipe 10 control the flexing of the diaphragm 15 while the action of the springs 27 regulate the pressure of the valve 20 upon the diaphragm 15 consequently rendering the device adjustable whereby the valve 20 will be shifted rearwardly when the fluid pressure reaches or exceeds a predetermined degree. The tension of the springs 27 is regulated for this purpose by means of locking nuts 29 threaded upon the rods 24 at opposite sides of the head 23.

It will be noted that should the diaphragm 15 become disrupted, the springs 27 surrounding the rods 24 will exert a sufficient pressure between the sliding head 22 and the diaphragm casing so as to cause the

valve 20 to seat upon the gasket 17 of the inlet pipe 10 to consequently cut off the flow of fluid into the chamber 11.

The compressor not shown for the fluid within the pipe 10 is operated by a motor having circuit wires 30 and 31 electrically connected to a stationary terminal 32 and a pivot switch point 33 respectively. The switch point 33 is normally maintained in contact with the terminal 32 and the circuit for the electric motor closed by any suitable means such as the leaf spring 34.

A plunger 35 is longitudinally slidable in spaced supports 36 and 37 with an insulated tip 38 upon one end adapted for engaging the point 33 and opening the switch at one extremity of the longitudinal movement of the plunger 35. A lever 39 is pivoted upon an arm 40 carried by the casing section 13 with a head 41 at one end freely positioned in a transverse slot 42 of the valve stem 21. A head 43 upon the opposite end of the rod 39 is freely positioned within a yoke 44 carried by the plunger 35 between the supports 36 and 37, it being evident that a movement of the valve stem 21 in either direction imparts longitudinal movement of the plunger 35 by means of the lever 39.

The gabled or V-shaped upper surface 45 of the yoke 44 is constantly engaged by the rounded end 46 of a leaf spring 47 and whereby the yoke 44 is snapped quickly in either opposite direction upon being shifted by the lever 39 until the spring end 46 passes slightly beyond the apex or ridge of the yoke 44.

The complete operation of the invention will be fully understood from this detail description thereof, the mechanism being set with a diaphragm 15 unflexed when the fluid pressure in the pipe 10 is normal. An increase in the fluid pressure flexes the diaphragm 15, rearwardly shifting the valve 20 and causing its stem 21 to rearwardly move the lower end of the lever 39 causing the upper end 43 thereof to force the yoke 44 and plunger 35 toward the switch point 33. When the yoke 44 passes the point illustrated in Fig. 2 of the drawing, the round end 46 will ride down the rearward side of the surface 45 causing the plunger 35 to move quickly forward engaging the insulated tip 38 against the switch point 33 and swinging said point to this circuit opening position out of contact with the terminal 32. The head 43 is thereby brought in contact with the rear end of the head receiving socket 48 of the yoke 44 whereby a

decrease in the fluid pressure caused by stopping the electrically operated compressor permits the springs 27 to return the valve 20 to its normal position shifting the plunger 35 rearwardly and releasing the switch point 33 for automatic contact with the terminal 32. The fluid pressure in the pipe 10 is thereby automatically maintained substantially constant through the control of the electric switch 32-33 by the actuation of the diaphragm 15.

While the form of the invention herein set forth is believed preferable, it will nevertheless be understood that minor changes may be made without departing from the spirit and scope of the invention.

What is claimed as new is:—

1. An automatic controlling device for fluid pressure piping comprising a casing having a chamber to which the end of the piping communicates, a metallic gasket formed within the chamber adjacent the outlet end of said pipe, said gasket effecting a valve seat for the end of the piping within said chamber, a flexible diaphragm transversely of the chamber, and a controlling valve resiliently maintained against the opposite side of the diaphragm from said seat adapted for automatically closing upon the diaphragm.

2. An automatic controlling device for fluid pressure piping comprising a casing having a chamber to which the end of the piping communicates, the said casing having an annular groove within the chamber formed by a central boss, a metallic gasket having its outer edge spun over into the annular groove, said gasket effecting a valve seat around the end of said pipe, a flexible diaphragm transversely of the chamber, and a controlling valve resiliently maintained against the opposite side of the diaphragm from said seat adapted for automatically closing upon the seat upon the accidental breaking of the diaphragm.

3. An automatic controlling device for fluid pressure piping comprising a casing having a chamber to which the end of the piping communicates, a metallic gasket formed within the chamber adjacent the outlet end of said pipe effecting a valve seat for the end of the piping within said chamber, a flexible diaphragm transversely of the chamber, and means adapted for automatically closing upon the seat upon the accidental breaking of the diaphragm.

In testimony whereof I affix my signature.
JOSEF ELLMAUER.
